COMPOSITE FENCE STRUCTURE

Eric R. Skilnik, Chicago, Ill.

Application December 30, 1935, Serial No. 56,642

5 Claims. (Cl. 256—22)

This invention relates to a composite structure. In the form illustrated herewith it is particularly embodied in a fence, although it is not limited to use in such a structure.

5 It has for one object to provide means for erecting a fence simply. Another object is to provide means for erecting a fence without the use of tools. The third object is to provide a fence or other composite structure in which the 10 parts may be assembled without the use of tools and may be fastened or locked together without the use of any additional pieces, such as keys, wedges, bolts or analogous members.

Other objects will appear from time to time in 15 the specification and claims.

The invention is illustrated more or less diagrammatically in the accompanying drawing, wherein:—

Figure 1 is a side elevation of a portion of a 20 fence;

Figure 2 is a plan view with parts broken away and parts in section;

Figure 3 is a side elevation of one of the standards;

25 Figure 4 is a plan view of an upper rail;

Figure 5 is a plan view of an upper rail positioned adjacent the rail of Figure 4 to indicate the assembly of the two in a fence;

Figure 6 is a plan view of a lower rail.

30 Like parts are designated by like characters throughout the specification and drawing.

1 indicates a main support which in this case is the ground. 2 are individual foundations for standards. These foundations may be of any

35 design or material. It is often convenient to have concrete or stone blocks to serve as foundations for the standards. To these foundations are secured standards 3 which may be of any shape but as in the form shown are of channel

40 section and slotted in at least two places as at 4 to provide seats or receiving portions for the upper and lower rails. The lower rail 5 is pro-

45 vided at suitable intervals intermediate its ends with slots 6 which may be of any size and shape but are, in the form here shown, generally straight and generally aligned with the longitudinal axis of the rail 5. To make the rail suit-

50 able for use in a structure in which two rails join at right angles, the rail may have at or near its end two slots 6 intersecting each other symmetrically and at right angles. This is not an essen-

55 tial feature but is usually an advantage. The rails 5 are of such size that they pass through and fit within the slots 4 in the standards 3.

Ordinarily, of course, since 5 is intended primar-

ily to act as a lower rail, it will be inserted through the lower slot 4.

The upper rails 7 are provided with slots 8 of any size and shape but in the particular form shown the slots are generally elongated and in alignment with the longitudinal axis of the rail 7. The slots are preferably shaped to provide different diameters. In the particular form here shown this is accomplished by an enlargement or notch 9 which may be formed anywhere throughout the length of the slot. To permit the use of the upper rails in the corner of structures where one rail meets another at a right angle, two such slots 8, 9 may be provided at the corner, meeting at right angles to each other. Thus when two 15 upper rails have their ends superimposed at right angles to each other the crossed slots of each rail are in register with each other and a picket may be inserted in the slot facing in either direction.

A suitable number of pickets 10 which may have curved or ornamental upper ends 11 is inserted in the slots. The pickets, as shown, are provided preferably below their centers, or even adjacent their lower ends, with downwardly faced tongues 12. In the form shown these tongues 20 contact the upper surface of the lower rail 5 and act as stops to limit the downward movement of the picket. Each picket is also provided, preferably above its center and adjacent its upper end with an upwardly or oppositely facing tongue 13. 25 When the pickets are made, both tongues are preferably severed along their sides and across one end and bent to an initial or partially bent position. Since the slots in the lower rail conform to the shape of the cross section of the 30 picket they do not permit either of the tongues to pass through. Since, however, the grooves in the upper rail are enlarged as at 9, for example, they 35 permit both tongues to pass through. After the pickets are in place with the lower tongue 12 resting on the upper surface of the lower rail 5, the upper tongue 13 is close to the lower surface 40 of the upper rail 7. It may be then bent further so that it extends, as shown in Figure 1, outwardly away from the surface of the picket a 45 distance sufficient to prevent its subsequent withdrawal through the enlargement 9 of the slot 8. In other words, the pickets are assembled first by merely being slipped through the slots in both rails, the lower tongue seats on the lower rail and 50 the upper tongue is then pushed far enough out of line so that it can no longer pass through the slot in the upper rail and in this manner the fence is assembled and cannot fall or be taken apart. 55

It will be realized that whereas I have herein shown and described a practical operative device, nevertheless many changes might be made in the size, shape, number and disposition of parts without departing from the spirit of the invention and I wish therefore that my showing be taken as in a sense diagrammatic.

The use and operation of my invention are as follows:

10 The structure will ordinarily comprise certain fixed supports or standards. These may be secured to a separate foundation, for example, by being driven into the ground or by being secured to foundations formed in the ground. It may 15 also, in the case of partitions, walls, shelves and the like, be secured to the foundation or floors of a building or room or other enclosed space. Whatever the exact details, there will in general be certain support or standard members which 20 are secured in position and are aligned to define the direction and the dimensions of the fence, partition, shelving or other structure to be erected.

25 The rails are inserted through the slots in the standards. It is to be understood that the rails might be secured to the standards in any other way but a convenient method is that shown in which the standards are of channel section and slotted to receive the rails. In general also all 30 of the lower rails will be identical with each other and all of the upper rails will be identical with each other, although these are not absolutely essential features.

If it be assumed that the standards are in position 35 and that the lower rails have been mounted in them, and that the upper rails have also been mounted in them, then the lower rails, with their straight slots, are so arranged that at the corner where one rail meets another the overlying slots 40 of each rail are in register with the slots of the other rail and the same is true of the slots in the upper rails. The pickets may then be inserted. The shape and size of the slot at or 45 near the end of the bottom rail where more than two rails are used, one above the other, are such that the picket may penetrate through at least the uppermost rail and usually through the bottom rail. Through that rail the picket may 50 penetrate but the tongue or projecting member may not. Hence it contacts one of the rails, usually the lowermost rail, and serves to position the picket vertically.

The problem now is to fasten the picket against 55 removal and for that purpose the upper tongue or projection, which has passed through at least some, and usually all except the lower rail, is forced farther outward, and thus extends beyond the laterally projecting portion formed in the slots in the upper rail or rails and so prevents 60 withdrawal. Thus the insertion of the pickets completes the fence and also ties the rails together at the corners because at that point, where the rails of each set overlap, the slots 65 intersect and a single picket passes through the slots of two adjacent rails and secures them together, and so the picket serves not only as its own fastening and positioning member but also as the fastening and positioning member for the rails themselves, and no special tool has been 70 necessary and no added part is necessary. A hammer and a simple chisel, screw driver or punch can be used to force the upper tongue or projection far enough out of line with the surface 75 of the picket within which it lies to prevent withdrawal of the latter from the rail into which it

has been inserted. In this manner the fence is assembled. While the projections or tongues are shown as partially formed at the time the fence pickets are assembled, it might, of course, be quite unformed and a prick punch or other tool 5 might be used to force it outwardly or it might be severed and left in place and then forced outwardly. It is ordinarily convenient, however, to sever it and force it initially partly outward, leaving it to be forced fully outward to the locking position after it has been assembled in the fence.

Although I have spoken of a fence, obviously a framework corresponding generally to the fence might be formed by the parts shown and in general if that were done the method of construction and assembly would be substantially the same as that shown in the present drawing. The rails would in that case serve to support shelving, flooring or other similar structural 20 members, and the invention, while it finds a ready use in the building of a fence, is not limited to that purpose.

I claim:

1. In a composite fence, a plurality of fixed 25 standards, rails positioned one above the other in said standards, one rail provided with a plurality of slots, another rail provided with irregularly shaped slots, each slot having a lateral enlargement intermediate its ends, and pickets 30 shaped to be positioned in said slots, each picket provided with a downwardly facing tongue positioned out of line with the plane of the picket, and provided also with an upwardly facing tongue positioned out of line with the plane of 35 said picket, the upper tongue originally being so disposed as to pass through the enlargement in the slot in the upper rail and being thereafter moved to a position preventing its passage and consequent withdrawal of the picket through 40 the slot.

2. In a composite fence, a plurality of fixed standards, rails positioned one above the other slidably in said standards, one rail provided with a plurality of slots, the slots adjacent the ends 45 of said rail intersecting the other at right angles, another rail provided with irregularly shaped slots, each slot having a lateral enlargement intermediate its ends, the slots at the ends of the said rail intersecting at right angles, and pickets positioned in said slots and holding said rails against sliding, each picket provided with a downwardly facing tongue positioned out of line with the plane of the picket, and provided also with an upwardly facing tongue positioned 55 out of line with the plane of said picket, the upper tongue originally being so disposed as to pass through the enlargement in the slot in the upper rail and adapted thereafter to be moved to a position preventing its passage and 60 consequent withdrawal of the picket through the slot.

3. In a composite fence, a plurality of fixed standards, slots in said standards, generally horizontally disposed, rails slidably positioned one 65 above the other in the slots of said standards, one rail provided with a plurality of slots, the slots adjacent the ends of said rail intersecting the other at right angles, another rail provided with irregularly shaped slots, each slot having 70 a lateral enlargement intermediate its ends, and pickets shaped to be positioned in said slots to hold said rails against sliding, each picket provided with a downwardly facing tongue positioned out of line with the plane of the picket, 75

and provided also with an upwardly facing tongue positioned out of line with the plane of said picket, the upper tongue originally being so disposed as to pass through the enlargement in the slot in the upper rail and adapted thereafter to be moved to a position preventing its passage and consequent withdrawal of the picket through the slot.

4. In combination in a fence, an upper and a lower rail, and a plurality of pickets, each picket having a downwardly faced outward projection below its center and an upwardly facing outward projection above its center, slots in said lower rail sized and shaped to permit the picket alone to pass therethrough, slots in said upper rail sized and shaped to permit said picket and projections to pass therethrough, the upper projection, after having passed through the rail, being forced outwardly to hold the picket against removal, and each rail having at its end crossed slots positioned at right angles to each other whereby a single picket is adapted to engage and hold in position a plurality of angularly disposed rails, each pair of crossed slots being the same in size and shape as the slots positioned in the remainder of the rail.

5. Means for erecting upon a plurality of fixed supports a composite fence structure comprising a plurality of identical pickets, each having a pair of projections, one below its center facing downwardly, another above its center facing upwardly, and a plurality of upper and lower rails, the lower rails being each provided with a series of straight, longitudinally aligned slots and having at their ends crossed slots, symmetrically positioned, meeting at right angles and being of the same size and shape as the slots in the remainder of the rail, the upper rails being identical with each other and provided with a series of generally longitudinally aligned slots, each slot having a lateral enlargement and adjacent its ends having crossed slots symmetrically positioned, said supports shaped to receive said rails, said lower projections in a completed fence contacting the upper surface of a rail, said upper projections in a completed fence being pressed outwardly beyond the lateral enlargement of the slots of said upper rail and preventing withdrawal of a picket.
